UNITED STATES PATENT OFFICE

146,757

DESIGN FOR AN EDUCATIONAL DEVICE TO TEACH CHILDREN TO READ A CLOCK

James A. Webb, Rochester, N. Y.

Application January 25, 1946, Serial No. 125,982

Term of patent 7 years

(Cl. D34—15)

To all whom it may concern:

Be it known that I, James A. Webb, a citizen of the United States, residing in Rochester, in the county of Monroe and State of New York, have invented a new, original, and ornamental Design for Educational Device to Teach Children to Read a Clock, of which the following is a specification, reference being had to the accompanying drawings, forming part thereof.

Fig. 1 is a front elevational view of an educational device to teach children to read a clock, showing my new design; and

Fig. 2 is an enlarged fragmentary cross section taken substantially on the line 2—2 of Fig. 1.

I claim:

The ornamental design for an educational device to teach children to read a clock, substantially as shown.

JAMES A. WEBB.
